Atys

Patented Aug. 7, 1928.

UNITED STATES PATENT OFFICE.

GERRIT VAN DAAM, OF KENMORE, NEW YORK.

STOOL.

Application filed June 27, 1927. Serial No. 201,769.

My invention relates to improvements in stool structures and the object of the invention is to construct a stool in which a footrest is provided, and a further object of the invention is to so attach the footrest to the stool that it can be swung upwardly towards the center seat supporting spindle in order to reduce the space taken up upon the floor and to enable the stool to be readily moved from one spot to another.

A further object of the invention is to incorporate a receptacle within the footrest portion of my stool which can be used for containing shoe polishing implements, and a further object of my invention is to make the stool adjustable in height so that it can be either used as a high stool or lowered so that the seat constitutes a step for enabling the user to reach the high shelves etc.

20 My invention consists of a stool constructed and arranged all as hereinafter more particularly described and illustrated in the accompanying drawings in which—

Figure 1 is a side elevational view of my stool showing the footrest in the downward functioning position.

Figure 2 is a plan view thereof.

Figure 3 is an enlarged cross sectional view of the rigid footrest portion of the stool showing the shoe brush receptacle contained therein, and

Figure 4 is an enlarged side elevational view of a fragmentary portion of the stool spindle showing the means for adjusting it in height, also the swingable portion of the footrest swung into the inoperative position.

The base portion of my stool consists of a substantially triangular frame 1 having three legs 2 each extending outwardly from one of its apexes, the lower ends or feet 3 of the legs being each furnished with a semi-spherical non-slipping foot member 4 formed of rubber or some like material. The frame 1 is preferably constructed of L shaped cross section to give lightness with strength and the upper face thereof is suitably recessed around the center orifice 5 to receive the outwardly extending horizontal flanges 6 of a receptacle 7 which depends from the frame, the flanges 6 being positioned flush with the upper face of the frame and suitably secured thereto by means of spot welding or in any other similar manner. 8 is a lid provided for the recess 7 being hinged thereto along its inner edge 9 and

furnished with a finger orifice 10 by means of which the lid can be swung upwardly into the position shown in dotted lines in Figure 1.

The rear apex 11 of the member 1 supports the lower end of an upwardly extending sleeve 12 in which a spindle 13 is slidably mounted, and 14 is a seat secured upon the upper end of the spindle. 15 is a spring catch furnished at a suitable height upon the side of the sleeve 12 for holding the lid 10 of the receptacle 7 in its open position.

16 is a vertical slot in the sleeve 12 extending from the vicinity of the upper end thereof to a point intermediately of its height, and 17 are a plurality of spaced apart bayonet catch slots which open into the slot 16 to receive a radially extending pin 18 upon the spindle 13 so that the spindle can be adjusted in height in respect to the sleeve 12. The upper ends 19 of each of the bayonet catch slots 17 are above the entrances 20 from the bayonet catch slots into the slot 16 so that the entrances 20 diverge into the bayonet catch slots. The object of this construction is to enable the stool to be lifted from one spot to another by lifting the seat 14 without having the pin 18 slide from its slot into the slot 16 and allowing the seat and the spindle 13 to be jerked upwardly. When the stool has been lifted by the seat it will be seen that the pin 18 will merely move to the upper end 19 of the bayonet catch slot in which it is contained and will not move into the slot 16 unless the seat and spindle 13 are partially rotated.

21 is the swingable portion of the footrest being substantially semi-circular in form and secured along its straight side 22 to the straight edge of the frame 1 by means of a suitable hinge 23, and 24 is a single leg depending from the vicinity of the outer end of the member 21 to constitute a support therefor when the footrest member is in the functioning position as illustrated in Figure 1. When the stool is in use the swingable footrest member 21 may be swung upwardly into the position as illustrated in Figure 4 wherein the leg 24 extends upwardly adjacent to the sleeve 12.

My stool is primarily designed for domestic purposes, particularly for kitchen use wherein the housewife very often requires a seat higher than a kitchen chair, and provided with some kind of a footrest to en-

able her to hold mixing bowls or other similar kitchen utensils upon her knee. My stool also performs an important function as a stepping means, as the seat 14 can be lowered to enable the user to step from the footrest 21 therein, to reach the high shelves etc. When the stool is not in use such footrest portion 21 can be swung into position as illustrated in Figure 4 wherein my stool 10 will not take up very much more space than the ordinary stool of three leg type, and also by providing the receptacle 7 in the frame for containing shoe brushes etc. my stool finds a ready use as a shoe cleaning stand.

15 From the foregoing description it will be apparent that I have devised a footrest stool of a very simple construction which will fulfill a variety of uses within the home and very materially add to the comfort and convenience of the housewife.

20 What I claim as my invention is:

1. In a device of the character described, the combination of a foot rest stool and a shoe cleaning stand, a frame, a plurality of 25 legs extending downwardly therefrom, seat supporting means extending upwardly from one side of the frame, a shoe cleaning implement containing box positioned interiorly of the frame, the lid of the box forming in

conjunction with the frame part of the foot 30 rest of the stool, and a shoe cleaning stand foot rest portion pivotally mounted upon the frame and adapted to normally lie in the same plane as the frame and box lid foot rest portion to constitute in combination therewith an extended foot rest for the stool and a shoe cleaning stand.

2. In a device of the character described, the combination of a stool and a shoe cleaning stand, a substantially triangular frame, 40 a plurality of legs each extending downwardly from one of the apexes of the frame, seat supporting means extending upwardly from one of the apexes of the frame, a shoe cleaning implement containing box positioned interiorly of the frame, the lid of the box forming in combination with the frame part of the foot rest of the stool, and a shoe cleaning stand foot rest portion pivotally mounted upon the side of the frame 45 opposite the apex from which the said supporting means extends, and adapted to normally lie in the same plane as the frame and box lid foot rest portion to constitute in combination therewith an extended foot rest for 50 the stool and a shoe cleaning stand.

GERRIT VAN DAAM.
